ATTORNEY,

UNITED STATES PATENT OFFICE.

KARL A. SIMMON, OF EDGEWOOD PARK, PENNSYLVANIA, ASSIGNEE TO WESTINGHOUSE ELECTRIC AND MANUFACTURING COMPANY, A CORPORATION OF PENNSYLVANIA.

LIQUID RHEOSTAT.

1,277,495.

Specification of Letters Patent. Patented Sept. 3, 1918.

Application filed December 10, 1914. Serial No. 876,442.

To all whom it may concern:

Be it known that I, KARL A. SIMMON, a citizen of the United States, and a resident of Edgewood Park, in the county of Allegheny and State of Pennsylvania, have invented a new and useful Improvement in Liquid Rheostats, of which the following is a specification.

My invention relates to liquid rheostats of the type that are provided with a continuous circulation of electrolyte, and it has special reference to means for cooling the electrolyte or dissipating the heat thereof.

One of the objects of my invention is to provide apparatus of the above-indicated class, which shall be simple and effective in arrangement, construction and operation, and which shall be particularly adapted to cool the entire body of circulating electrolyte by continuously dissipating a large amount of heat from a relatively small portion of the electrolyte.

In a more specific aspect, it is the object of my invention to provide cooling apparatus which shall be arranged in multiple relation to a portion of the main circulating system, and which shall be adapted to dissipate energy in the form of latent heat of vaporization contained in relatively small volume of electrolyte which is continuously by-passed through it.

When liquid rheostats are employed upon powerful electric locomotives of large capacity where economy of weight and space is essential, it becomes necessary to use liquid rheostats through which the electrolyte is continuously circulated, and the size and power of the locomotive is then limited to a great extent by the capacity of the circulating system to dissipate the heat given up to the electrolyte.

It is, of course, possible to force the entire body of electrolyte through some form of cooling apparatus whereby the heat of the electrolyte may be directly dissipated, but in systems of this type the choking effect of the cooling apparatus is such as to necessitate pumps of excessive size, while the proportions of the cooling apparatus are also prohibitive.

According to my invention, I propose to overcome the difficulties hereinbefore mentioned and to provide adequate means embodying auxiliary apparatus of relatively

small size for accomplishing the desired result.

In the accompanying drawing, Figure 1 is a view, partially in section and partially in side elevation, of apparatus embodying my invention, and Fig. 2 is a semidiagrammatic view in elevation of a modified form of my invention.

Referring to Fig. 1, the apparatus shown comprises a liquid rheostat 1, an electrolyte-containing reservoir 2, a pump 3, auxiliary cooling apparatus 4 and a fan 5.

The rheostat 1 is provided with a bottom discharge opening 8 in which is placed a tubular combined discharge and regulating valve 9 that is adapted to be raised and lowered in position by any suitable means (not shown) for the purpose of closing the discharge opening 8 and fixing the height of the electrolyte which is continuously supplied to the rheostat through an inlet pipe 10. The specific construction of the movable discharge and regulating valve 9 is not material to my present invention except as it contributes to the performance of necessary functions in the operation of the system as a whole, and any other suitable devices for performing similar functions may be employed. The rheostat 1 is located directly above the reservoir 2 and the electrolyte flowing through it is discharged therein.

The pump 3, cooling apparatus 4 and fan 5 are also merely illustrative of any form of devices for performing their respective duties. The pump 3 receives electrolyte from the reservoir 2 through a suction pipe 11 and forces said electrolyte through the inlet pipe 10 to the rheostat 1.

The cooling apparatus 4 comprises a containing tank 14 having a plurality of plates 15 that are alternately secured to opposite sides thereof and are inclined in a downward direction, the length thereof being somewhat less than the width of the tank 14 to provide a space between the free ends thereof and adjacent sides of the tank. A pipe 16 communicates with the upper end of the tank 14 above the upper plate 15 and is connected to the main inlet pipe 10 adjacent to the discharge side of the pump 3. A suitable deflecting barrier 17, which may constitute an integral portion of the pipe 16, projects into the inlet pipe 10 just above

the point of connection of the pipe 16 therewith, although it may not be necessary in all cases. The object of the deflecting barrier 17 is to partially obstruct the pipe 10 and 5 to cause a building up of pressure at the lower end of the pipe 16 whereby electrolyte is forced upwardly in the tank 14. The lower end of the tank 14 is connected to the suction pipe 11 by means of a pipe 10 18. Moreover, the fan 5 communicates with the lower end of the tank 14 through a pipe 19 for the purpose of introducing thereto a cooling medium, such as air. An outlet 20 is provided at the top of the tank 15 14 for permitting the escape of heated air and vapor.

Assuming the apparatus to occupy the positions shown and the pump 3 and fan 5 to be in operation, the electrolyte within 20 the reservoir 2 is drawn into the pump 3 and forced upwardly, the main body thereof being delivered through the inlet pipe 10 to the rheostat 1, while a relatively small volume is by-passed through the pipe 16 to 25 the cooling apparatus 4.

When the rheostat 1 performs its function of absorbing electrical energy in accordance with customary practice, it will be understood that the energy is transformed to heat 30 which is absorbed by the continuous flow of electrolyte. A portion of the heated electrolyte is continuously delivered to the upper end of the cooling apparatus 4 from whence it flows in a zig-zag path down 35 across the several plates 15 and is thus brought into contact with the forced ventilating air which rises between said plates and is permitted to escape through the outlet 20.

40 In this manner a relatively large amount of heat is dissipated continuously from the small portion of the electrolyte that traverses the cooling apparatus 4, so that the electrolyte which is returned to the main 45 circulating system through the pipe 18 is of comparatively low temperature, and, in mixing with the main body of circulating electrolyte maintains it in a sufficiently cool condition to insure proper operation.

50 It is seen, therefore, that the cooling apparatus occupies very little space and is capable of dissipating heat at a rapid rate to maintain the main body of electrolyte at a temperature within operating limits.

55 Reference may now be had to Fig. 2, which discloses apparatus of a similar nature to that already set forth, with the exception that the cooling apparatus 4 is located at a height sufficient to permit the 60 return pipe 18^a to carry the cooled electrolyte by gravity into the inlet pipe 10. Thus, the heat of a part of the circulated electrolyte is directly dissipated in the cooling apparatus and the cooled electrolyte is 65 delivered to the inlet pipe 10 and mixed with

the main body of electrolyte before being delivered to the rheostat 1.

Obviously my invention may be embodied in apparatus, the structural features and arrangement of parts of which differ materially from those herein set forth, and I, therefore, desire that only such limitations shall be imposed as are indicated in the appended claims.

I claim as my invention:

1. The combination with a liquid rheostat and means for continuously circulating electrolyte therethrough, of auxiliary apparatus traversed by a relatively small portion of the circulating electrolyte for cooling all of 80 said electrolyte by continuously dissipating the heat in the electrolyte traversing said auxiliary apparatus.

2. The combination with a liquid rheostat and means for continuously circulating electrolyte therethrough, of cooling means for by-passing a portion of the circulated electrolyte and for dissipating the heat contained therein.

3. The combination with a liquid rheostat 90 and means for continuously circulating electrolyte therethrough, of auxiliary means associated in multiple relation with a portion of the circulating means for cooling the entire body of circulating electrolyte by continuously dissipating a large amount of heat from a relatively small portion of the entire body of electrolyte.

4. The combination with a liquid rheostat, a body of electrolyte, and pumping means 100 and a piping system for continuously circulating said electrolyte through said rheostat, of cooling apparatus connected in multiple relation to a portion of said piping system for continuously dissipating heat 105 from a relatively small body of electrolyte that passes through it.

5. The combination with a liquid rheostat, a body of electrolyte, and pumping means and a piping system for continuously circulating said electrolyte through said rheostat, of branch piping connected to the main piping system on the discharge side of said pumping means and to another point of the system, and cooling apparatus included in 115 said branch piping.

6. The combination with a liquid rheostat and means for circulating electrolyte therethrough, of means for directly cooling only a portion of said circulated electrolyte.

7. The combination with a liquid rheostat and means for circulating electrolyte therethrough, of a cooling device associated with said circulating means for directly dissipating heat from only a portion of the circulated electrolyte.

8. The combination with a liquid rheostat and means embodying a pumping device for continuously supplying electrolyte thereto, of apparatus located between said pumping 130

device and the rheostat for cooling a portion of the electrolyte delivered to said rheostat.

9. The combination with a liquid rheostat and means embodying a pumping device for continuously supplying electrolyte thereto, of cooling apparatus connected in multiple relation to a portion of said means for directly cooling a portion of the electrolyte.

10. The method of cooling a body of heated liquid, which consists in circulating the entire liquid continuously and in bypassing and simultaneously cooling a relatively small portion thereof.

11. The method of cooling a body of heated liquid, which consists in continuously

circulating said liquid and in continuously circulating a relatively small portion thereof through a cooling means.

12. The combination with a liquid rheostat containing a body of liquid and means for continuously circulating said liquid through a plurality of passages in multiple relation, of means for continuously dissipating the heat of the liquid that is circulated through one of the said passages.

In testimony whereof, I have hereunto subscribed my name this 30th day of Nov., 1914.

KARL A. SIMMON.
